PANEL.

No. 16,228.

Patented Sept. 8, 1885.

Fig. 1.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,228, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., the same consisting of a panel, of which the following is a specification, reference being had to the accompanying photographs, forming part hereof.

Figure 1 is a plan view of a panel having my new design formed upon it. Fig. 2 is a longitudinal section of the same.

Similar letters of reference indicate like parts.

My design consists of a series of raised bars, A B, in juxtaposition and extending trans-

versely across the panel. These bars have a rounded upper surface. The bars A are greater in width than the bars B, which alternate with them. The bars B are of sharper curvature than the bars A.

I claim—

The design for surface ornamentation of walls, the same consisting of a panel, substantially as herein shown and described, consisting in alternating wide and narrow elevations A B, having rounded surfaces and extending transversely across said panel.

FREDERICK MANKEY.
